[57] ABSTRACT

This cinch includes a webbing assembly including a pair of longitudinal straps extending in parallel rela-

tion between and around a straight bar of a pair of cinch buckles, then inclined to cross over and extend to the outside at the center, with the ends of each strap overlapped at the center. A cross strap encircles the longitudinal straps at the center, including the overlapped ends and with its own ends overlapped. The cross strap also forms a loop at each end to receive a ring for a breast collar strap and a flank cinch strap. The center of the webbing assembly is stitched, through the cross strap, and the longitudinal straps are stitched together adjacent each buckle. The straight bars of the buckles produce a straight pull on both the parallel and inclined portions of the longitudinal straps. The webbing assembly is enclosed by a double walled cover having an olefin or similar pile on the outside and angular extensions at the center, both to the front and rear, conforming in shape to the webbing assembly. These extensions provide a greater bearing area for the cinch and minimize interference with the horse's elbows. The cover also has slots, on the underside, through which the respective buckles and rings extend, thereby providing adequate padding for said buckles and rings.

1
CINCH

This invention relates to cinches, and more particularly to a cinch utilized for attaching a saddle to a horse.

Among the objects of this invention are to provide a cinch which will produce more comfort for the horse and be less apt to produce cinch sores; to provide a cinch which is adapted to fit well forward on the brisket of the horse; to provide a cinch having an adequate bearing surface; to provide such a cinch which will produce sufficient space for clearance between the cinch and the elbows of the horse; to provide such a cinch in which the hardware used has adequate padding and bearing surfaces; to provide such a cinch in which there is a straight pull between the breast collar ring and the flank cinch ring; to provide such a cinch in which there is an essentially straight pull between the cinch buckles, thereby tending to minimize wadding, twisting or turning of the cinch; to provide such a cinch which is completely washable and the parts of which are different from leather in being resistant to rot and mildew and having sufficient strength to avoid breakage; and to provide such a cinch which is relatively easy to manufacture and will be long wearing and durable in use.

Additional objects and the novel features of this invention will become apparent from the description which follows, taken in conjunction with the accompanying drawings, in which:

FIG. 1 is a top plan view of a cinch constructed in accordance with this invention.

FIG. 2 is a bottom plan view of the cinch of FIG. 1.

FIG. 3 is a top plan view of a webbing assembly which is placed inside a fleece or pile cover.

FIG. 4 is a bottom plan view of the webbing assembly.

FIG. 5 is a cross section, on an enlarged scale, taken along line 5—5 of FIG. 3 through the longitudinal center of the webbing assembly.

FIG. 6 is a cross-section, on an enlarged scale, taken along line 6—6 of FIG. 1, near one end of the fleece or pile cover.

FIG. 7 is a fragmentary section, on an enlarged scale, taken along line 7—7 of FIG. 2, at one edge at the center of the fleece or pile cover.

FIG. 8 is a perspective view, on a reduced scale, of the cinch, as it is fitted to a horse.

FIG. 9 is a side perspective, on a considerably reduced scale, of the cinch as mounted on a saddled horse.

A cinch C constructed in accordance with this invention is shown in FIG. 9 as mounted on a horse H and attached to a saddle S by means of a latigo 10. The cinch C engages the brisket 11 of the horse, while a breast collar strap 12 extends forwardly and a flank cinch strap 13 extends rearwardly from the cinch, the former extending to a breast collar 14 and being connected, if desired, to a nose band or tie down 15. Conventional reins are provided but are not shown, for clarity of illustration. Flank cinch strap 13 extends rearwardly to a flank cinch 16, attached to the saddle by a conventional latigo 17. Shown in FIG. 8 is the latigo 10 at each side, by which the saddle is attached to the cinch C, as well as the breast collar strap 12 extending forwardly and the flank cinch strap 13 extending rearwardly. In FIG. 9 is shown the breast collar strap 12

2

extending between the front legs 19 and 20 of the horse.

The cinch C engages the brisket 11 at a forward position, where the brisket is solid, rather than rearwardly over the more flexible part where there is more cartilage between the ribs and the brisket. Nevertheless, there is plenty of room between the cinch and the elbow 21 of each of the front legs of the horse, as will be pointed out later.

10 The cinch of this invention comprises a fleece or pile cover F which acts as a padding member and encloses a webbing assembly W. As in FIGS. 1, 2 and 6, fleece cover F is formed of a fabric provided with a dense pile having the characteristics of an olefin pile, preferably of a type which is utilized in hospitals under bedridden patients, to prevent bed sores, in order to prevent cinch sores on the horse. The fleece or pile cover is formed from top and bottom halves 24 and 25, which are cut to shape to provide rectangular sides 26 having rounded corners and a forwardly and rearwardly extending, angular portion 27 at the center of the completed cover. The extending portions 27, which cause the cover F to conform in shape to the webbing assembly W, as described below, provide a greater bearing 15 area for the cinch and also provide greater room for movement of the front leg elbows 21 without increasing the width of the cinch. The two halves 24 and 25 are placed with the pile of each half facing the pile of the opposite half, and the edges 28 are sewn together, as by stitching 29 of FIG. 6. Each half of the cover is, of course, cut with proper allowance for the sewn edges. After the edges are sewn, the cover is turned inside out, as through one of a pair of slots 30, adjacent opposite ends of the sides thereof, through which cinch strap buckles 31 extend in the completed cinch. Additional slots 32, as in FIG. 2, through which rings 33 extend for connection to the breast collar strap 12 and flank cinch strap 13, respectively, are also provided, as by slots in the bottom half of the cover F. A slot 32 for each of rings 33 may be conveniently provided, as in FIG. 7, merely by omitting some of the edge stitching 29 at the position of the rings. The webbing assembly W of FIGS. 3 and 4 may be inserted within the cover, as the cover is turned inside out.

45 As in FIGS. 3 and 4, the webbing assembly W comprises a pair of longitudinal straps 35 and 36 and a center cross strap 37, each formed of a tightly woven webbing of suitable material, such as nylon, which is both washable and resistant to rot and mildew, as is the fleece or pile cover F. Each end of each strap 35 and 36, as well as the center of each web strap, is attached to cross strap 37, as by stitching 38. The ends of each strap 35 and 36 are also overlapped between the cross strap 37, which, as in FIG. 5, is a single strap extending over both the top and bottom of the overlapped ends and centers of straps 35 and 36, with the ends 39 of strap 37 overlapped. Each strap 35 and 36 is disposed in parallel relation with the other strap throughout the length of the webbing assembly, on the bottom side thereof, as in FIG. 4, and extends as a loop 40 over a straight bar 41 of a buckle 31, the straps 35 and 36 being positioned on opposite sides of a buckle tongue 42. From the buckle 31, each strap 35 and 36 is inclined to extend to the opposite side of the center of the webbing assembly, crossing over the other strap at a cross-over area 43. The longitudinal straps are further connected together by stitching 44, between the buckle

and the cross-over area 43. Loops 46, formed by the cross strap 37, as in FIG. 5, engage the respective rings 33. Each angular portion 27 of the fleece or pile cover, as will be evident, accommodates the angular effect of the web straps, with the cross strap being at the center 5 of the angular central portions 27.

Both the buckles 31 and rings 33 are formed of a suitable corrosion resistant material, such as stainless steel. Since the upper and lower reaches of cross strap 37 are stitched together throughout substantially the length 10 thereof, the cross strap will resist twisting or turning, although the pull on rings 33 is normally much less than the pull on buckles 31. While rings 33 may be of conventional circular shape, the straight bar 41 of each buckle 31 is highly desirable, since such a bar produces 15 a straight pull on the parallel portions of straps 35 and 36, as well as on the inclined portions of these straps. Thus, the straight bars 41 of buckles 31 materially assist in minimizing wadding at the buckles or twisting or 20 turning of the cinch. Since slots 30 for buckles 31 and 25 slots 32 for rings 33 are on the underside of the cinch cover, the hardware has adequate padding and bearing surfaces. The central extensions 27 of the fleece or pile cover provide additional bearing surface for the cinch, while the inner ends of the inclined portions of straps 35 and 36 transmit a commensurate portion of the pull 30 on cinch buckles 31 to the bearing area under the extensions 27. Due to the curved form of the cinch, as in FIG. 8, when placed on a horse, an effective pull of the inclined ends of straps 35 and 36 on the bearing areas 30 of extensions 27 is enhanced. Thus, the effective bearing area of the cinch is increased without the necessity of increasing the width thereof, which would increase the possibility of the elbows 21 of the front legs of the 35 horse striking the cinch during movement.

As will be evident from the foregoing, a cinch constructed in accordance with this invention fulfills to a marked degree the objects and requirements hereinbefore set forth. Although a preferred embodiment of this invention has been illustrated and described, it will be 40 evident that other embodiments may exist and that various changes may be made therein, without departing from the spirit and scope of this invention.

What is claimed is:

1. A cinch comprising:

a padding member having a longitudinal dimension sufficient to extend beneath the rib cage of a horse and lateral extensions at the center providing additional bearing area; 45
a webbing assembly corresponding in shape to the 50 padding and having means producing a force against said padding member, including said extensions; and
a cinch buckle having a straight bar at each end of said webbing, whereby an essentially straight pull 55 at the ends of said webbing is produced and said lateral extensions produce a minimum of interference with the elbows of the front legs of said horse.

2. A cinch as defined in claim 1, wherein:

said padding member comprises a washable fabric provided with a pile.

3. A cinch as defined in claim 2, wherein:

said pile has the characteristics of an olefin pile.

4. A cinch as defined in claim 1, wherein: said padding member is a cover which encloses said webbing assembly.

5. A cinch as defined in claim 4, wherein: said cover is provided with slots on the underside through which said cinch buckles extend.

6. A cinch as defined in claim 1, wherein: said webbing assembly comprises longitudinal straps which extend in parallel relation between and around a bar of each cinch buckle, then are inclined to cross over to the outside of the parallel portions of said straps at the center of said webbing assembly.

7. A cinch as defined in claim 6, including: a cross strap disposed centrally of said webbing assembly and attached to both the parallel and inclined portions of said longitudinal straps.

8. A cinch as defined in claim 7, wherein: said cross strap extends across both the underside and the top side of the central portion of said longitudinal straps.

9. A cinch as defined in claim 1, wherein: said padding member is a cover which encloses said webbing assembly and comprises two halves, each formed of a washable fabric having a pile on the outside, the edges of said two halves being stitched together within said cover; said cover having generally rectangular side portions provided with rounded corners and an angular, forwardly and rearwardly extending portion at the center thereof;

said cover is provided with slots on the underside through which said buckles extend;

said webbing assembly includes a pair of longitudinal straps which extend in longitudinal, parallel relation between said cinch buckles, then around the straight bar of the corresponding cinch buckle, on opposite sides of a tongue of said cinch buckle, then are inclined to cross over and extend to a position on opposite sides of the center of said parallel portions, the ends of the inclined portions of each strap being overlapped at the center of the webbing assembly, stitching connecting said longitudinal straps between said cross-over area and the adjacent cinch buckle;

a cross strap extending across both the top and the bottom of said longitudinal straps and enclosing both said parallel portions and said overlapped ends of said longitudinal straps, the ends of said cross strap also being overlapped;

stitching connecting the top and bottom reaches of said cross strap and its overlapped ends and the center of said parallel portions and said overlapped ends of said longitudinal straps;

said cross strap forming a loop at each end thereof, to receive a ring for attachment of a breast collar strap or the like and a flank cinch strap or the like received in said loops; and

said cinch cover being provided with an aperture on the underside of each angular portion through which the corresponding ring extends.
